1,367,746 A 2/1921 Kent*Primary Examiner* — Paula Allen Greene(74) *Attorney, Agent, or Firm* — Holzer Patel Drennan(57) **CLAIM**

The ornamental design for a headset, as shown and described.

DESCRIPTION

FIG. 1 is a perspective view of a headset showing our new design.

FIG. 2 is a front elevational view thereof.

FIG. 3 is a back elevational view thereof.

FIG. 4 is an outer side elevational view thereof.

FIG. 5 is an opposite outer side elevational view thereof.

FIG. 6 is a top plan view thereof; and,

FIG. 7 is a bottom plan view thereof.

In the drawing, the claimed design is defined by the shaded surfaces; the broken lines depict environment that forms no part of the claimed design.
